UNITED STATES PATENT OFFICE

BURGESS W. SMITH, OF ROCHESTER, NEW YORK, ASSIGNOR TO THE TODD COMPANY, INC., OF ROCHESTER, NEW YORK, A CORPORATION OF NEW YORK

DESIGN FOR PAPER FOR BANK CHECKS AND THE LIKE

Application filed November 18, 1931. Serial No. 41,776. Term of patent 14 years.

To all whom it may concern:

Be it known that I, BURGESS W. SMITH, a citizen of the United States, residing at Rochester, in the county of Monroe and State of New York, have invented a new, original, and ornamental Design for Paper for Bank Checks and the Like, of which the following is a specification, reference being had to the accompanying drawing, forming part thereof.

The figure is a view of a sheet of paper showing my new design applied thereto. Such paper may be used for bank checks, drafts, notes, securities, and other certificates of value, and the like.

I claim:

The ornamental design for paper for bank checks and the like, substantially as shown.

BURGESS W. SMITH.
